PARACHUTE PACK

John Raymond Cuthbert Quilter,
Woking, EnglandApplication September 6, 1946, Serial No. 695,132
In Great Britain October 19, 1945

6 Claims. (Cl. 244—148)

1

This invention relates to parachute packs for aviators and more particularly to packs of the seat type.

The invention has for its main object to provide an improved seat-type pack which is readily detachable from the harness, so that the pack may be left in place at the aviator's seat while he is free to move about wearing the harness but unencumbered by the parachute; this is especially desirable in tropical or sub-tropical conditions, where the weight that can be comfortably supported is very limited.

A further object of the invention is to provide a detachable parachute pack in which the lift webs are made readily adjustable to suit individual wearers, while maintaining the feature of automatically taking the load upon these lift webs and not upon auxiliary adjustable webs.

Another object of the invention is to provide an improved detachable parachute pack of the seat type, which overcomes many of the disadvantages of the ordinary detachable seat-type pack; for example, with an ordinary pack of this type, the aviator is not only encumbered by the weight of the parachute but if he has to walk about while wearing the pack, it is liable to descend to the level of his knees or even lower, due to the lift webs pulling out of the pack. Thus the lift webs may become loose enough to let the pack turn over facing his body when he is in the act of jumping from the aircraft, making the deployment of the parachute impossible or difficult.

Other objects and advantages will hereinafter appear from the following description of a preferred embodiment, given with reference to the accompanying drawings in which:

Fig. 1 is a sectional elevation of the improved pack, as seen from the front of the seat, with an aviator's harness coupled thereto, the harness being shown in the position of wear.

Fig. 2 is a perspective view of the pack, as seen obliquely from beneath, the pack being in open condition and the shroud lines partly withdrawn.

Fig. 3 is a sectional detail of the connection between one of the adjusting strops and the respective lift web.

As illustrated in Figs. 1 and 2, the parachute pack 11 comprises a flat rectangular base or frame 12, made for example of wire and covered

with textile material; this base is fitted on its upper surface with a cushion 13 and on its lower surface with two rows of looped tapes 14 for zig-zag engagement of the shroud lines 15 in the customary manner. The four edges of the base are fitted with cover flaps 16 for retaining the pack in closed condition after stowage of the parachute, the closure of these flaps being controlled by the usual rip-cord device 17, operated by means of a handle 18 which the aviator attaches to a convenient point of the harness or of his garment after taking his seat.

In the center of the base, there is mounted a dependent loop of flexible wire 19 which can be traversed by a retaining pin 20 made of spring steel wire bent to V-shape; a narrow pocket 21 stitched to the base material is adapted to receive the legs of the retaining pin after it has been threaded through the wire loop. The pin 20 can be withdrawn from the pocket and loop by the drag of a cord 22 extending in the opposite direction from the apex of the pin to one of the shroud lines 15; the attachment to the latter and the length of the drag cord 22 are so selected that the pin 20 will be withdrawn while the shroud lines are still slack and not yet wholly drawn out from the pack, as shown in Fig. 2.

The two side cover flaps 16 are formed with apertures such as slots 23 adjacent to the edges 30 of the base, through which slots lift webs 24 connected to the shroud lines 15 by shackles 25 pass to the exterior; their outer extremities are formed with loops 26, preferably reinforced by liners 27, and secured to quick-action coupling devices 28 of suitable or well-known type whereby they can be connected to the lower ends of the main lift webs 29 worn as part of the harness. These main lift webs may be made of nylon cords running side by side, for example eight cords to each web, for the sake of lightness and coolness in hot climates; they are preferably guided along tunnels 30 beneath flaps 31 extending over the shoulders of the wearer, the flaps being normally held down upon his garment by press studs 32 or the like which yield to the pull of the lift webs as the parachute comes into operation. The harness may be arranged as described in my pending application Serial No. 649,237, filed Feb. 21, 1946.

At the points where the coupling devices 28

are secured to the lift webs or connectors 24 coming from the pack, the looped portions 26 of these connectors engaging with cross-bars 33 upon the coupling devices 28 are reinforced or bound with outer loops 34 secured by the same rivets or stitching 35 as the inner loops 26 and their liners 27; the outer loops carry sliding bar buckles 36 which engage frictionally with adjusting strops 37 passing out from the pack through the same slots 23 as the lift webs or connectors 24, the free ends 38 of these strops hanging down in the position of wear so that they can be tightened readily by a downward pull. Inside the pack 11, these adjusting strops 37 extend parallel with the lift webs or connectors 24 and directly beneath them, being loosely held in relative position by collars 39 slideable along the adjusting strops 37 and the lift webs or connectors 24; the connector 24 at each side of the pack is preferably made as a doubled length of webbing or like material, with the loop 26 formed at the middle of the entire length and the two ends 24a looped for attachment of the shackles 25, in which case the collar 39 need only engage the lower of the two superposed halves of the web. Between the two collars, the adjacent ends of the adjusting strops 37 fit closely against the under surface of the base, in the gap between the shackles 25 from which the shroud lines 15 commence their zigzag stowing transverse to the line of the lift webs or connectors; these ends of the strops are fitted with eyelets or grommets 40 which are engaged successively over the wire loop 19 projecting from the middle of the base, the retaining pin 20 being then passed through the end of the loop 19 and slipped into its pocket 21 upon the base. As the shroud lines 15 are stowed zigzag fashion in their retaining tapes, the drag cord 22 extending from the pin 20 to the shroud line will be left loose; the pin therefore retains the adjusting strops 37 engaged with the wire loop 19 until the parachute has almost completed the extraction of the shroud lines, as seen in Fig. 2, the pin being then withdrawn by the drag cord 22 and the adjusting strops freed so that the pull of the shroud lines will be taken wholly by the lift webs 24.

In operation, the parachute pack will be laid upon the seat of a chair or like support, with the lift webs or connectors 24 and the adjusting strops 37 hanging loosely from the pack but connected together by the buckles 28 on each side, and the rip-cord device and its handle 18 laid on the floor to one side; an aviator wearing his harness including the main lift webs 29 will be able to take his seat upon the cushion 13 on top of the pack, to couple up the lift webs or connectors 24 to his main lift webs 29, by means of the quick-action couplings 28, to attach the rip-cord device to his waist belt or garment, and to adjust the tension of the main lift web to a comfortable fit by pulling down the free ends 38 of the strops. If now he desires to leave his seat without disconnecting the pack from his harness, he will be free to do so and to walk about while wearing the pack, without danger of the lift webs 24 accidentally pulling out and thereby allowing the pack to fall down, with the consequences mentioned above.

What I claim is:

1. A parachute pack enclosing a parachute, shroud lines and lift webs, said lift webs extending out from the pack for attachment of their extremities to a harness, in combination with means for adjusting said lift webs after attachment to the harness, said adjusting means comprising

flexible members extending out from the pack beside the respective lift webs, releasable means for locking together the ends of said flexible members inside the pack, and adjustable means for connecting the external ends of said flexible members to the extremities of the lift webs attached to the harness.

2. A parachute pack enclosing a parachute, shroud lines and lift webs, said lift webs extending out from the pack for attachment of their extremities to a harness, in combination with means for adjusting said lift webs after attachment to the harness, said adjusting means comprising flexible members extending out from the pack beside the respective lift webs, releasable means for locking together the ends of said flexible members inside the pack, adjustable means for connecting the external ends of said flexible members to the extremities of the lift webs attached to the harness, and means for releasing said locking means by the emerging shroud lines when the pack is opened.

3. A parachute pack enclosing a parachute, shroud lines and lift webs, said lift webs extending out from the pack for attachment of their extremities to a harness, in combination with means for adjusting said lift webs after attachment to the harness, said adjusting means comprising flexible members extending out from the pack beside the respective lift webs, and frictional buckles secured to the extremities of said lift webs, said buckles being adjustably engaged by the external ends of said flexible members.

4. A parachute pack enclosing a parachute, shroud lines and lift webs, said lift webs extending out from the pack for attachment of their extremities to a harness, in combination with means for adjusting said lift webs after attachment to the harness, said adjusting means comprising flexible members extending out from the pack beside the respective lift webs, and frictional buckles secured to the extremities of said lift webs, said buckles being adjustably engaged by the external ends of said flexible members with the free extremities of said flexible members hanging down from the respective buckles so that said flexible members can be tightened for adjustment by a downward pull on their extremities.

5. A parachute pack enclosing a parachute, shroud lines and lift webs, said lift webs extending out from the pack for attachment of their extremities to a harness, in combination with means for adjusting said lift webs after attachment to the harness, said adjusting means comprising flexible members extending out from the pack beside the respective lift webs, releasable means for locking together the ends of said flexible members inside the pack, said locking means comprising a member fixed inside the pack and adapted to engage the adjacent ends of said flexible members, a retaining pin engageable with said fixed member to hold said adjacent ends engaged therewith, and a tie from said pin to the shroud lines, the withdrawal of the shroud lines by the emerging parachute disengaging said retaining pin from said fixed member, and adjustable means for connecting the external ends of said flexible members to the extremities of the lift webs attached to the harness.

6. A parachute pack enclosing a parachute, shroud lines and lift webs, said lift webs extending out from the pack for attachment of their extremities to a harness, in combination with means for adjusting said lift webs after attachment to the harness, said adjusting means comprising

flexible members extending out from the pack beside the respective lift webs, releasable means for locking together the ends of said flexible members inside the pack, the internal ends of said flexible members extending parallel with the respective lift webs from said locking means to common apertures in the pack, means for holding the parallel portions of said internal ends and lift webs loosely in relative position, and adjustable means for connecting the external ends of said flexible members to the extremities of the lift webs attached to the harness. 10
